(57) **CLAIM**

The ornamental design for a “drinking and misting bottle with obround carrying loop”, as shown and described.

DESCRIPTION

FIG. 1 is a top right perspective view of a drinking and misting bottle with obround carrying loop showing our new design;

FIG. 2 is a bottom left perspective view thereof;

FIG. 3 is a front elevational view thereof;

FIG. 4 is a left side elevational view thereof;

FIG. 5 is a rear elevational view thereof;

FIG. 6 is a right side elevational view thereof;

FIG. 7 is a top plan view thereof; and,

FIG. 8 is a bottom view thereof.

The broken line showing in the figure drawings are included for the purpose of illustration and form no part of the claimed design.

1 Claim, 7 Drawing Sheets
